MULTIPLE PINHOLE MAGNIFIER

Gerald Kessler, 388 Cranberry Road,
Youngstown, Ohio 44512

Filed Feb. 22, 1971, Ser. No. 117,864

Term of patent 14 years

Int. Cl. D16—06

U.S. CL. D57—1

FIG. 1.

FIG. 2.

FIG. 3.

FIG. 1 is a top plan view of a multiple pinhole magnifier showing my new design;

FIG. 2 is a rear elevation thereof; and

FIG. 3 is a side elevation thereof, the opposite side is a mirror image of the side shown.

I claim:

The ornamental design for a multiple pinhole magnifier, as shown and described.
